UNITED STATES PATENT OFFICE.

HENRIK BÖVING, OF NEW YORK, N. Y., ASSIGNEE TO WESTERN ELECTRIC COMPANY,
INCORPORATED, OF NEW YORK, N. Y., A CORPORATION OF NEW YORK.

ELECTRICAL PROTECTIVE DEVICE.

1,324,334.

Specification of Letters Patent.

Patented Dec. 9, 1919.

Application filed August 16, 1917, Serial No. 126,498. Renewed June 11, 1919. Serial No. 303,475.

To all whom it may concern:

Be it known that I, HENRIK BÖVING, a citizen of the United States, residing at New York, in the county of New York and State 5 of New York, have invented certain new and useful Improvements in Electrical Protective Devices, of which the following is a full, clear, concise, and exact description.

This invention relates to devices for protecting electrical circuits from abnormal voltages, lightning and similar discharges and more particularly to protective devices of the type adapted to provide a ground connection for a circuit when its potential is 15 raised to an abnormal value.

The type of protector commonly used for protection of circuits of low normal operating voltage consists essentially of two electrodes spaced apart a few thousandths of an 20 inch, one of these electrodes being connected to ground and the other connected to one wire of the line to be protected. In order that a protector of this type may afford the required degree of protection and at the 25 same time not require an excessive amount of maintenance, it is not only necessary that the electrodes be spaced apart the proper distance, but also that the design be such that this separation is not altered by service 30 conditions. In protectors so designed that the conducting blocks or electrodes are separated by means of a sheet of insulating material, more or less trouble is experienced due to the formation of a bridge of conducting 35 material over the edge of the separator as the result of repeated discharges. On the other hand, in the case of protectors not employing insulating separators but depending upon the conducting electrodes being properly spaced in an insulating block, difficulty 40 has been experienced in obtaining a cementing means which does not cold-flow at normal operating temperatures.

It is the object of the present invention to 45 provide a protector in which the electrodes are secured in place by means of a material which is non-hygroscopic, non-inflammable and which is not subject to cold flow under normal temperatures.

50 A further requirement of this material is that it shall soften and become plastic in case the blocks attain a temperature involving a fire hazard. To accomplish this result, the invention provides a protector in 55 which electrodes are secured in place by

means of a low-melting point glass, this material being free from the defects inherent in the various cements used heretofore.

In the accompanying drawing, Figure 1 is a side elevation of a protector embodying 60 the features contemplated by this invention; and Fig. 2 is a cross-sectional view along the line 2—2 of Fig. 1.

The protector shown in the drawing comprises a block 3 of porcelain or similar insulating material in which are mounted the opposing electrodes 4, 5 of conducting material, preferably carbon. These electrodes are accurately spaced a definite distance apart by means of a gage inserted in the 65 opening 6 and after the blocks have been heated, are secured in place by means of threads or fillets 7 of low-melting point glass. For this purpose a lead-borate glass 70 consisting of approximately 85% lead-oxid 75 and 15% boric acid has been found to be particularly suitable.

This material, which is non-inflammable and non-hygroscopic, becomes plastic at approximately 360° C. and is not subject to 80 cold flow at normal operating temperatures. As the method of mounting these electrodes is well understood in the art, being illustrated, for example, in Williams Patent 588,206, August 17, 1897, it is thought to be 85 unnecessary to illustrate the method in the present case.

In service the electrodes 4 and 5 engage respectively a ground plate and a line spring, the latter being under considerable 90 tension. In the event of a high resistance cross with a power or lighting circuit, the arc formed between the electrodes, if allowed to continue, would generate sufficient heat to draw the temper from the spring and 95 cause a dangerous fire hazard. However, with the proposed construction the glass becomes plastic before this dangerous temperature is reached and the tension of the protector spring forces the electrodes together, thereby providing a low resistance path to ground and eliminating all danger from arcing.

What is claimed is:

1. In a protective device, conducting 105 blocks held adjacent each other but separate from one another, supporting means for one of said blocks, said block being held in position in said supporting means by a low-melting point glass,

2. In a protective device, a pair of conducting blocks held adjacent to but separate from one another, one of said blocks comprising an electrode of conducting material secured to a member of non-conducting material by means of a low-melting point glass.
3. In a protective device, a pair of conducting blocks held adjacent to but separate from one another, one of said blocks comprising an electrode of conducting material secured to a member of non-conducting material by means of lead-borate glass consist-

ing of approximately 85% lead-oxid and 15% boric acid.

4. In a protective device, a pair of conducting blocks held adjacent to but separate from each other, one of said blocks comprising a carbon electrode secured to a porcelain member by means of a low-melting point glass.

In witness whereof, I hereunto subscribe my name this 15th day of August, A. D. 1917.

HENRIK BÖVING.
